UNITED STATES PATENT OFFICE.

AMOS B. PAXON, OF NEWSTEAD, ASSIGNOR OF ONE-HALF TO JOHN E. ALtenberg, OF AKRON, NEW YORK.

WASHING-MACHINE.

SPECIFICATION forming part of Letters Patent No. 270,976, dated January 28, 1883.

Application filed November 10, 1882. (No model.)

To all whom it may concern:

Be it known that I, AMOS B. PAXON, a citizen of the United States, residing at Newstead, in the county of Erie and State of New York, have invented certain new and useful Improvements in Washing-Machines, of which the following is a specification, reference being had therein to the accompanying drawing, in which the figure represents a longitudinal 10 cross-section through the entire device.

This invention consists in the employment of an upright fixed wash-board, which is ribbed and perforated, and a movable dasher or presser, also ribbed and perforated, and combining with each a hinged valve, by which, when the dasher is operated, a continuous rotary action is given to the water in the tub or box, thereby constantly changing the water about and greatly aiding in cleansing the 20 clothes, all as hereinafter fully explained.

A represents a box or tub having a rounded bottom, and provided with a plug to let out the water. It is open at the top and stands on legs.

25 B is a vertical stationary wash-board standing near the center of the box. It has longitudinal ribs *a a a* and a series of holes between each rib for the water to flow through. At the back of this board B, and working 30 close to the bottom of the tub, is a hinged wooden valve, *b*, its operation to be presently explained.

C is a movable wash-board or dasher attached to a frame, C', and operated by the 35 handle D, the frame swinging in bearings *d* in the side pieces of the box, as shown. This movable board is also ribbed and perforated, like the board B, and has a valve, *c*, hinged to the back at the upper part of said board, 40 as shown in the drawing. Thus the valve *b* on the vertical stationary board B is set at the bot-

tom, and the valve *c* on the movable board C near the top, on the outside, so that when the handle D of the dasher C is raised it closes both of the valves against the boards, leaving 45 a space into, which the water pours, chiefly over the top of the boards, while by dropping the handle the dasher compresses the clothes against the stationary board B, lifting both valves and creating a flow of water both ways 50 through the perforations in both boards. A whirling action of the water is kept up as long as the machine is operated. This describes the operation, which, by merely lifting the handle, changes the water in and about the 55 clothes by sucking it and the dirt through the perforations, making a reciprocating action by alternately opening and closing the valves *b* and *c* by raising and dropping the handle D. The pressure or squeeze of the clothes between the boards is very great, and the valves giving the rotary action to the water are very 60 important in aiding to carry away the dirt and dirty water from the clothes.

I do not claim the ribs and perforations, as 65 such are old.

I claim—

In a washing-machine, the combination of the tub or box A, stationary ribbed and perforated wash-board B, having a valve, *b*, secured to the back thereof, and adapted to close upon the lower half of board, with the dasher C, provided with the valve *c*, secured to the back thereof, and adapted to close upon the upper half of dasher, all constructed to 70 operate substantially as herein set forth.

In testimony whereof I affix my signature in presence of two witnesses.

AMOS B. PAXON.
